UNITED STATES PATENT OFFICE.

HERMANN HALTER, OF MUNICH, GERMANY, ASSIGNOR TO S. J. HEIBERG, OF CHICAGO,
ILLINOIS.

RAILROAD BED.

Application filed December 8, 1919. Serial No. 343,447.

To all whom it may concern:

Be it known that I, HERMANN HALTER, a subject of the King of Bavaria, and residing at Munich, Germany, Kaulbachstrasse 60a, have invented certain new and useful Improvements in Railroad Beds (for which I have been granted a Swiss Patent No. 79,444, June 19, 1918, and a British Patent No. 140,116), of which the following is a specification.

It has been found by experience that a permanent good foundation or bed for a railroad and a constant uniform support for all of the sleepers cannot be made by spreading road material loosely on the railroad track.

This lack of permanence is specially prevalent at the rail joints where the effect produced by the weight of passing trains is greatest.

A bed of uniform substance extending beneath the track is not capable of offering a higher resistance at the joints where the effect is greatest. For this reason the sleepers at the joints of rails on new or comparatively recently laid tracks lie at most places on hollows and continually require renewed packing or tamping, and if this is neglected the fish plates keep breaking off, the rail ends bend, the whole structure becomes loose, and hollows form at the rail joints with all their evil consequences. This will happen in spite of strengthening the rails and fish-plates, of making the sleepers broader and placing them closer together near the joints, using the best kind of bed material, providing special layers of bedding material and of increasing the height of the road material foundation.

A permanent good and uniform rail support can only be obtained by enhancing the carrying capacity of the bed at the points where the stress on the rails is especially heavy.

This object of the present invention is attained by embedding rigid grids or trellises in the road material beneath the sleepers as near as practicable to their bottoms, the members of these grids increasing in width from top to bottom down to a certain point and then decreasing from the said certain point to the bottom.

These grids or trellises impart an increased carrying capacity to the rail bed by decreasing the liability of the parts of which the

bed is made up to shift apart from each other. The pieces of road material or parts constituting the bed are forced wedge-like into the funnel-shaped openings of the grid, so that they are prevented from giving way to vertical and lateral pressures to which they are subjected. To the roughness of the parts, which is accountable for the carrying capacity of the bed, a mechanical binding force is added, which is due to the grid and which is not detrimental to the elasticity and the free passage of water through the bed. By placing the grid high up in the bed near to the bottoms of the sleepers it is made to act as a common support over which the pressure of two adjacent sleepers, each bearing an end of two adjacent rails, is evenly distributed. The surfaces of the grid or trellis support, which slope towards each other, are peculiarly adapted to completely divide the pressure and to distribute it evenly over the layers of the railbed and the ground beneath.

A method of carrying out the invention is illustrated in the drawing in which,

Fig. 1 is a cross section through a track supplied with the grids or trellises.

Fig. 2 is a longitudinal section of the same, and

Fig. 3 is a plan view of a fragment of track in which the road metal is omitted.

Fig. 4 shows on a larger scale a section of a grid or trellis of Fig. 3 on the line a—b, the grid or trellis being made of reinforced concrete.

In order that the grids may be securely embedded in the material forming the track, and that they may not sink down, their bottom surfaces are made as broad as possible and to slope upwards. The top surfaces of the grids however are made as small as possible in order that the pressure may bear less upon these surfaces than upon the sloping inner surfaces of the openings in the grids so as to promote the effect of pressure distribution.

The size of the openings in the trellises is such that the material constituting the bed, which may be unevenly distributed due to displacement by the lower sloping surfaces whilst shifting the grids to and fro before they are got into their final positions, may enter into and find room in the openings.

The surfaces of the grid or trellis must

not be made too large, for this might cause depressions of the bed by the grid.

The grids or trellises must be laid upon a layer of bed material at least 4 inches thick, upon which they will participate in the elastic motions of the bed.

I claim:

1. A reinforcing grid for road beds of railroads, comprising a flat body portion 10 adapted to be embedded in the comminuted material of the road bed and having a plurality of vertical openings therethrough, the walls of said openings converging gradually from the upper surface of the body portion 15 to near the base thereof and to bind and hold together the comminuted material above the body portion, and said walls at their lower ends abruptly flaring into the base to present inclined anchoring surfaces at the 20 lower side of the grid.
2. A reinforcing grid for the road beds of railroads, comprising a body portion

adapted to be embedded in the comminuted material of the road bed and having a plurality of spaced apart bars arranged in intersecting and angular relation to one another, said bars gradually tapering from near their bases to their upper edges to provide substantially funnel-shaped openings in the body portion adapted to receive therein the comminuted material for distributing lateral pressure exerted in a downward direction on the road bed, said bases of the bars having beveled marginal edges to provide laterally facing anchoring surfaces 30 adapted to engage the material of the road bed and prevent shifting of the grid in the road bed.

In testimony whereof I affix my signature in presence of two witnesses.

HERMANN HALTER.
